UNITED STATES PATENT OFFICE.

THOMAS B. MILLER, OF SEATTLE, WASHINGTON, ASSIGNOR TO WIRELESS INSTRUMENT CO., OF SEATTLE, WASHINGTON, A CORPORATION OF WASHINGTON.

MOUNT FOR CRYSTAL DETECTORS

1,277,627.

Specification of Letters Patent.

Patented Sept. 3, 1918.

Application filed January 2, 1917. Serial No. 140,243.

To all whom it may concern:

Be it known that I, THOMAS B. MILLER, a citizen of the United States, and resident of the city of Seattle, county of King, and 5 State of Washington, have invented certain new and useful Improvements in Mounts for Crystal Detectors, of which the following is a specification.

My invention relates to detectors for use 10 in radio signaling and consists in an improved construction of the type of detectors which are known as crystal detectors.

The object of my invention is to produce 15 a detector of this type which is of rugged and reliable construction, not likely to be deranged and its operation interfered with by jars, concussions, or other rough treatment, one which may be easily adjusted to place 20 its contact member at any point upon the surface of the crystal, in which the crystal and its complemental contact members are inclosed and not subject to outside influences and in which, once a satisfactory contact is obtained, this may be retained.

25 My invention comprises the peculiar and novel constructions which are involved in the device and which will be hereinafter shown and then particularly defined by the claims.

30 In the accompanying drawings I have shown the type of construction which is now most preferred by me, although aware that this construction may be considerably varied without essentially departing from the principles upon which my invention is based.

Figure 1 is a plan view of my device with the top portion removed.

Fig. 2 is an inside plan view with said top portion removed, the sliding contact member being shown with its supporting arm in section.

Fig. 3 is a section through the assembled device, the plane of section being taken through the pivot of the swinging arm.

45 Fig. 4 is a central section taken through a modified type of construction.

Fig. 5 is a plan view of this modified construction.

In the use of crystal detectors, that is, 50 the detectors of the type in which a fine point is placed in contact with a mineral, usually a natural crystal, good results are obtained when a proper contact can be maintained. However, it is difficult to obtain and maintain a proper contact upon

the crystal and for this reason detectors of this kind are often unsatisfactory. Such detectors quite generally have the crystal and the contact point exposed to dust and atmospheric influences, and furthermore, 60 means are not usually provided whereby adjustment may be had to any point upon the surface of the crystal. Further, when such adjustment is obtained, that is found to work well, the permanence of this condition 65 cannot be obtained with certainty.

In constructing my device, I employ a base member 1 which has a cylindrical shell 10, forming a casing within which the operating parts are mounted. In the construction shown in Figs. 1, 2 and 3, the base 1 and the shell 10, which form the casing proper, are made as separate pieces, being secured by any suitable means, as by screws. In the construction shown in Fig. 4, these 75 two parts are integral with each other.

In the type of construction shown in Figs. 1, 2 and 3, I mount a contact point upon the base 1 and the crystal upon the case 10, the crystal in this case being mounted so as to 80 be rotatable and the contact point being mounted for movement in a path which extends from a point which substantially coincides with the axis of the rotation of the crystal outwardly to a point which extends 85 substantially to the outer limits of the crystal. The crystal 2 is mounted in a holder 20, as by being embedded within a mass of cement 21, contained in the hollow of the holder 20. The holder 20 is mounted to be 90 turned about an axis. The manner of doing this, shown in Fig. 3, consists in providing the cup 20, which forms the holder with a stem 22, which is secured into a boss of a metal plate 23. This boss forms a neck 95 which has a bearing in a plate 24 which is secured to the casing 10. The casing 10 should preferably be of an insulating material or in some other manner the crystal holder should be insulated from the other 100 parts.

The plate 23 is also provided with a knob or cap 25 for engagement with the hand so that the crystal may be turned into any angular position desired. As a means for 105 holding the crystal holder in any adjusted position, I have inserted a spring washer 26 between the holder 20 and the inner surfaces of the plate 24 upon which it is turned. This will provide sufficient frictional re- 110

sistance to hold it in any position in which it may be placed.

Within a recess in the base 1 is placed a lever 3, which lever is pivoted at 30, and 5 at its opposite end is provided with means by which it may be swung upon its pivot. Said means may be of various constructions. The construction herein shown consists in providing a swinging end of the lever 3 with 10 a slot 31 which receives a pin 32 carried by a lever 4, which lever is pivoted at a convenient point within the casing, as 40, and has its swinging end extending without the casing, being at this end provided with a 15 knob 41, or any other construction by which it may be conveniently manipulated. The section 10 of the casing is provided with a recess section 11 of such extent as to accommodate the swing of the lever 4. The lever 20 3 is provided with a spring plate 33 secured by its base to the lever and carrying the contact point 34, which is made of steel or other metal. In this manner the contact point is yieldingly supported so that it will 25 be able to maintain contact with the face of the crystal, irrespective of whether the piece of this crystal is or is not a close approximate of a plane. The triangular shape of the spring member 33 secures rigidity of 30 the support against movement of the said support and the lever 3, while making it easily yielding in a direction perpendicular to this plane.

The pivot 30 is employed as one lead. 35 The other lead consists of the screw 50 by which the spring contact bar 5 is supported. This spring contact bar is curved so as to fit against the outer surface of the crystal holder 20. In this manner electrical contact is made with the crystal. By swinging 40 the lever 4 to one side or the other the contact point 34 may be moved from a position which coincides with the axis by turning the crystal to a point extending to the extreme 45 outer part of the crystal holder. This movement, combined with the rotation of the crystal, makes it possible to utilize the entire surface of the crystal for contact with the contact point 4.

50 In the construction shown in Figs. 4 and 5, the crystal holder, or cup 20, is mounted with the base 1. In this case the crystal holder is not rotatable. The contact point 34 is upon the end of an arm 35 which has 55 a pivot section 36 extending through the cap member 6, which cap member is mounted to rotate in a plate 7 which is secured to the outer part of the casing 10. The casing 10 should be of an insulating material, while 60 the plate 7 and the portion 6 of the rotatable cap should be of metal or conducting material. In this case, a lead wire 70 passes through the body of the casing and connects with the plate 7. The rotative member 6 is provided with a knob 60, secured

hereto, by which it may be turned, said knob being preferably of nonconducting material, and having a recess 61 in its outer surface in which is placed a finger 62, which is secured to the axis portion 36 of the contact member. 70

A scale 63 may be made upon the knob 60, which, with the pointer 62, may be used to give an indication as to the position of the contact point 34. The axis, upon which 75 this contact point turns, is placed eccentric to the axis of turning of the member 6. The length of the arm 35 is such that the contact point may be made to swing over a path which extends from the axis of rotation outwardly. This, together with the rotation of the member which carries this contact arm, 80 will enable bringing the contact point in contact with any point upon the face of the crystal. 85

By the constructions herein illustrated, the crystal and the member which contacts therewith, are placed within an inclosed case where they are not affected by dust, dirt, and atmospheric conditions. Further, it is 90 possible to easily adjust the device so as to obtain the contact of any point upon the crystal. Further, the points are so constructed that when once adjusted in favorable condition, this adjustment may be maintained. By reason of this, one of the chief objections of the crystal detector is obviated. Also, by reason of these same facts, jarring or shaking of this detector prevents de- 95 arrangement of the adjustment. I have 100 found by experience that this detector will maintain its adjustment even when violently jarred.

What I claim as my invention is:

1. A mount for a crystal detector comprising a closed casing and a rotatable closure therefor, a crystal mounted upon one of said parts within the casing and a contact arm eccentrically pivoted upon the other, and means for swinging said arm. 105 110

2. A mount for a crystal detector comprising a casing, a rotatable closure therefor, a crystal carried by one of said parts within the casing and a spring contact arm eccentrically pivoted upon the other part to 115 carry its point over a path extending from a central position outward, and means extending without the casing for adjusting said point.

3. A mount for a crystal detector comprising a casing, a rotatable closure therefor having a crystal holder within the casing, an arm eccentrically pivoted within the casing, a contact point yieldingly carried by said arm and movable by the swinging of 120 125 said arm from a central position outwardly, and means for swinging said arm from without the casing.

4. A mount for a crystal detector comprising a casing, a rotatable closure there- 130

- for having a crystal holder within the casing, an arm eccentrically pivoted within the casing, a contact point yieldingly carried by said arm and movable by the swinging of 5 said arm from a central position outwardly, a pivoted controlling lever having actuating engagement with the first named lever and extending to without the casing.
5. A mount for a crystal detector comprising a casing, a rotatable closure therefor having a conductive crystal holder within the casing, a yielding conductor carried by the casing and engaging the crystal holder,
- a lead extending from said conductor to without the casing, a second lead extending 15 within the casing, a lever eccentrically pivoted within the casing and connected with said second lead, a contact member carried by said lever and adapted to engage the crystal, said point of engagement being movable by the swing of said lever from a central position outwardly, and means for swinging said lever from without the casing.
- Signed at Seattle, Washington, this 23rd day of December, 1916.

THOMAS B. MILLER.
